US00D865930S

(12) **United States Design Patent** (10) **Patent No.:** **US D865,930 S**
Bradley et al. (45) **Date of Patent:** **** Nov. 5, 2019**

(54) **HUMIDIFIER**

(71) Applicant: **D-M-S Holdings, Inc.**, West Des Moines, IA (US)

(72) Inventors: **Samuel Bradley**, Mundelein, IL (US); **Fernando Sanchez**, Berwyn, IL (US); **Hao Chen**, Shanghai (CN)

(73) Assignee: **D-M-S HOLDINGS, INC.**, West Des Moines, IA (US)

(**) Term: **15 Years**

(21) Appl. No.: **29/612,426**

(22) Filed: **Aug. 1, 2017**

(51) **LOC (12) Cl. 23-04**

(52) **U.S. Cl.**

USPC **D23/356**

(58) **Field of Classification Search**

(74) *Attorney, Agent, or Firm* — Fredrikson & Byron P.A.

(57) **CLAIM**

Applicant claims the ornamental design for a humidifier, as shown and described.

DESCRIPTION

A portion of the disclosure of this patent document contains material that is subject to copyright protection. The copyright owner has no objection to the facsimile reproduction by anyone of the patent document or the patent disclosure, as it appears in the Patent and Trademark Office patent file or records, but otherwise reserves all copyright rights whatsoever. The following notice shall apply to these elements: Copyright © 2017 D-M-S Holdings, Inc., All Rights Reserved.

FIG. 1 is a side elevational view of a first side of a humidifier of Applicant's design;

FIG. 2 is a side elevational view of a second side thereof, the second side being opposite the first side;

FIG. 3 is a side elevational view of a third side thereof, the third side being adjacent to the first side and the second side;

FIG. 4 is a side elevational view of a fourth side thereof, the fourth side being adjacent to the first side and second side and being opposite the third side;

FIG. 5 is a top plan view thereof;

FIG. 6 is a bottom plan view thereof;

FIG. 7 is an exploded perspective view thereof; and,

FIG. 8 is a bottom perspective view of a portion thereof in FIG. 7.

The broken lines showing parts of the article form no part of the claimed design.

1 Claim, 8 Drawing Sheets
